UNITED STATES PATENT OFFICE.

ALFRED KAUFMAN, OF NEW YORK, N. Y., ASSIGNOR TO F. D. MACK, OF NEW YORK, N. Y., AND C. M. PRANKARD, OF PORT WASHINGTON, NEW YORK.

HYDROCARBON-VAPOR GENERATOR AND BURNING DEVICE.

1,151,599.

Specification of Letters Patent. Patented Aug. 31, 1915.

Continuation in part of application Serial No. 660,505, filed November 15, 1911. This application filed January 23, 1914. Serial No. 813,857.

To all whom it may concern:

Be it known that I, ALFRED KAUFMAN, a subject of the Emperor of Germany, and a resident of the city, county, and State of 5 New York, have invented certain new and useful Improvements in Hydrocarbon-Vapor Generator and Burning Devices, of which the following is a specification.

This invention relates to apparatus for 10 generating gas from hydrocarbon and for burning the gas.

The object of the present invention is a simple device which will burn hydrocarbon without the production of soot or disagreeable odor in an efficient and reliable manner for heating and lighting.

Another object is the combination of the various elements in such manner that maximum heat is given with a minimum amount 15 of fuel, and with as few movable parts as possible.

Another object is a gas-generating mechanism so arranged and operated as to prevent the deposit of soot on the essential elements thereof.

Specifically, a part of my invention consists in a perforated plate arranged to be slid into position a short distance above the wick while the wick is lighted and to be slid 20 into position through the non-luminous part of the flame which is, at that time, used to preliminarily heat the device, and therefore by means of the structure shown the perforated plate is placed in position without 25 the deposit of any foreign matter, such as soot, thereon.

The above objects may be carried out by the means, or their equivalents, specifically described hereinafter and shown in the accompanying drawings, in which—

Figure 1 is a side elevation of the complete device; Fig. 2 is a section on line 2—2 of Fig. 1; Fig. 3 is a section on line 3—3 of Fig. 4, with the burner tube attached; Fig. 45 4 is a plan view of a modification with the burner tube removed; Fig. 5 is a view of the perforated plate 22; Fig. 6 is a view of the perforated plate 16; Fig. 7 is an enlarged 50 view of the burner tube with the flame through which the plate 16 is passed; Fig. 8 is a

view similar to that of Fig. 7 with the perforated plate 16 in position; and Fig. 9 is a modification showing a round wick and plate adapted to be placed in position there-over.

In the drawings, 1 represents a hydrocarbon fuel reservoir of any suitable shape and size. In Figs. 1, 2 and 3 it is shown as rectangular and forms the base of the device. Rising from the reservoir is a wick tube 2 adapted to accommodate a wide, flat wick, and of sufficient length so that no substantial amount of heat will be transmitted to the reservoir 1. This tube may be 60 soldered, or otherwise secured to the reservoir. In this tube is a wick 12 which is adapted to be raised or lowered by means of the thumb piece 3 in the well-known manner.

A table 4 having four projecting legs 13 is mounted on top of the reservoir and is rigidly secured thereto by any suitable means. This table has a rectangular opening therein in which is placed a rectangular 75 member 5 having a frusto-pyramidal portion 14 adapted to be placed over the wick tube 2, but leaving a space between the inside of the part 14 and the outside of the wick tube 2 sufficient for the entrance of 80 enough air to produce a blue flame along each of the sides of the wick, as will more fully appear hereinafter. A perforated plate 22 is preferably placed in the opening between the portion 14 and the wick tube 85 so as to more evenly regulate the draft for the wick flame.

Arranged in the upper part of the portion 14 are guide ways 15 adapted to receive a perforated plate 16, which preferably extends entirely across the opening in the portion 14. The position of these guide-ways, and therefore the plate, when in normal position, is a short distance above the top of the wick and is so situated that 90 when the perforated plate 16 is removed and the wick is lighted to preliminarily heat the device, the perforated plate 16 can be slid into position in the guide-ways through the non-luminous portion of the 95 flame. This feature is of considerable importance for the reason that the plate 16 can

- be entirely removed from the device while it is being heated up, and can then be slid into position so as to stifle the flame, without its being necessary for the plate to pass through the luminous or carbon-carrying portion of the flame, whereby a deposit of soot would be inevitable. The height of the flame, and therefore the height of the non-luminous portion of the flame, can be regulated by adjusting the position of the wick by the thumb-piece 3, so that the plate can be placed in position through the non-luminous part of the flame, as above described.
- 15 The perforated plate 16 may be slid into position sidewise, that is to say, it may enter along one of the long sides of the flame and pass through it the short way. In the present form of the apparatus it passes in end-
20 wise of the flame and this is the preferred way of inserting the plate. In the case of a round wick, as shown in Fig. 9, the screen while being placed into position, will necessarily pass through the flame in both ways,
25 because when it is first inserted it will pass sidewise through the flame and as it is pushed across the wick it will successively pass through the flame lengthwise and then sidewise again. It has been found by nu-
30 merous experiments that even though the perforated plate 16 be slid into position, it must be placed therein through the non-luminous portion of the flame. If it is slid, or otherwise placed in position, through the
35 luminous part of the flame, comparatively large volumes of black smoke will be the result and the perforated plate will be heavily coated with lamp-black. On the other hand, if the flame is so adjusted that the plate will
40 pass through the non-luminous portion, no black smoke whatever will be observed and no lamp-black or soot deposit will be made on the plate. In placing the plate in position through the non-luminous portion of
45 the flame it will be observed that the flame recedes a short distance in front thereof through its entire course across the wick, so that no soot whatever is deposited upon the plate. There is another advantage of
50 the removable feature of the plate 16 in that, during the preliminary heating of the device, no vapor is deposited thereon whereby it might become inefficient through the partial closing of the small perforations therein.
55 Mounted above and on the part 14 is a mixing or burner tube 6. This tube may be secured to the part 14 by means of screws passing through projections 11 which may be integral with the part 14, or it may be attached in any other suitable way. This tube is preferably made up from a cylinder of suitable material by flattening the lower portion of the cylinder into the shape shown in Figs. 1 and 2 and may be heat insulated
60 if desired. The tube when completed has an

elongated opening across the bottom, said opening having rounded ends, and from the bottom along the sides, the tube flares outwardly, and from the bottom along the edges it converges, so that the top is practically 70 round. Removably fastened on the top of the tube 6 is a perforated plate 10. The tube is also provided with openings 17 preferably entirely around its lower portion for the purpose of admitting air. The holes are 75 preferably placed quite close to the plate 16 just above the same so that the air entering will come in at right angles to the course of the vapor or gas coming through the plate 16 whereby a complete mixture of the gas 80 and air takes place. The air may be otherwise admitted to the tube 6 with satisfactory results.

It will be noted that the plate 16 separates the wick chamber in the part 14 from 85 the mixing chamber in tube 6, but for the communication through the perforations of the plate 16, so that there is a fuel chamber or reservoir, a wick chamber in the part 14 and a mixing chamber in the tube 6 all separate as above described.

Rising from the table 4 are four posts 8, one of which passes through each of the legs 13 and is secured thereon by means of nuts which are adapted to fit on the threaded 95 portions of the posts 8. The screw-threaded portions of the posts also go into screw-threaded holes in the top of the reservoir and serve to hold the table 4 and the parts supported thereby in position on the reservoir. Mounted on the top of the posts 8 is a suitable plate 7, on which is mounted a grating 9 of ordinary construction. The plate 7 is secured to the posts by means of nuts which fit on the threaded portions of 100 the upper ends of the posts 8. The length of the posts is such that the grating 9 comes a short distance above the top of the perforated plate 10 so that any article which may be placed upon the grating would be 110 heated by the flame produced on the plate 10.

The part 14, at one end, has a cut-away portion of sufficient size to permit the insertion of a lighted match or other means to ignite the wick when the plate 16 is removed. The plate 16 has a down-turned portion 23 of suitable size to cover this opening during the normal operation of the device. The portion 23 of the plate 16 acts as a handle by which it can be removed from and placed 115 into position. There is a chain 24 fastened to the plate 16 so that it may be removed from the guide-ways and be prevented from getting mislaid or lost. The plate 16 is shown as a thin piece of perforated metal, 120 but if it is found desirable it may be reinforced along its sides in any suitable way.

The plate for use on round wicks is much the same as that for a flat wick, except, of course, its shape. This plate differs also 130

therefrom in that there is an opening in the center thereof, as shown in Fig. 9, in order that the wick flames may have sufficient air to support them.

The preferred form of my device, as shown in Figs. 1, 2, 6, 7 and 8, has only one movable part, and this part, the plate 16, is positively guided in its movements and is firmly held in position in the device. This is an important feature of the device because there is nothing to get out of order when used by those unskilled in mechanical devices. The device illustrated in the drawings, which were made from a full-size model, has been extensively operated over a long period of time, and has, in every instance, operated entirely satisfactorily.

The reservoir may be so arranged that it can be slid out from under the table 4 in order that the wick may be lighted and can then be placed back into position to temporarily heat the parts in which case no opening in the portion 14 for lighting the wick, nor the downward projection of the plate 16, will be necessary. This construction is shown in Figs. 3 and 4. The essential parts of the device shown in these figures are the same as previously described. There are necessarily some changes by reason of which the burner may be removed from under the tube in order that it may be lighted. In this modification the base 18 has a sheet metal portion 19 rising therefrom. The posts 8 are fastened in this plate 19 by means of nuts. The table 4 has four posts 20 passing therethrough, which also may be fastened by bolts or otherwise to the plate 19. The table 4 is supported a short distance above the plate 19 in order that air may be admitted through the perforated plate 22 fastened to the bottom of the table 4. The part 19 has a portion cut away on one side thereof through which the reservoir 1 is adapted to slide, and the table 4 has an opening in one end thereof through which the wick tube passes. This perforated plate 22 also has an opening to accommodate the wick tube. Fastened on to the wick tube is a member 21 which is adapted to close the opening in the frusto-pyramidal part 14 of the table 4 in order to cut off any air which might otherwise enter through this opening. When it is desired to light the lamp, the reservoir and wick tube are drawn out and the wick is lighted and adjusted and is then placed back in position in order to heat up the burner tube and other parts. The perforated slide plate 16 is removed with, or prior to the drawing out of the reservoir to light the wick, and is subsequently slid into position, as above described. With the above-noted changes, this modification operates in the same way as the one previously described, and which operation is as follows:—The plate 16 is removed, the wick

turned up so that it can be lighted through the opening of the part 14, and is adjusted to give a smokeless flame. After it has been burning for a sufficient time to heat up the burner tube and other parts, the plate 16 is slid into position through the non-luminous part of the flame. When the plate 16 is in its normal position the flame is divided into two small blue flames along the outer edges of the wick, which, by means of their intense heat, vaporize the fuel drawn up by the wick. This vapor passes through the plate 16 into the lower part of the tube 6 and is there thoroughly mixed with the air coming in through the perforations at the bottom of the tube. By means of this arrangement the tube 6 can be wholly unobstructed, which adds to the efficiency of the device. This mixture of air and gas then passes through the tube 6 and is lighted above the perforated plate 10 at which point a blue non-luminous and odorless flame is produced which has very high temperature. The amount of vapor and therefore the size of the flame on the plate 10 can be increased or decreased by moving the wick up or down by means of the thumb-screw 3. When the lamp is thus started it will operate indefinitely unless it is purposely extinguished.

Having described my invention, what I claim as new, and desire to secure by Letters Patent, is:—

1. In a hydrocarbon burner, the combination of a fuel reservoir, a wick in communication therewith, a mixing chamber above said wick, a perforated plate between said wick and said chamber adapted to be slid into position through the non-luminous part of the flame after the wick has been lighted and the parts heated and a perforated plate at the upper end of said chamber.

2. In a hydrocarbon burner, the combination of a fuel reservoir, means provided with guide-ways supported above the reservoir, a perforated slide plate removably held in the guide-ways, a wick tube between said reservoir and said perforated plate, a burner tube above said plate and a burner at the free end of said tube.

3. In a hydrocarbon burner, the combination of a fuel reservoir, a wick in communication with said reservoir, a member supported above the reservoir and having a raised portion provided with guide-ways, a wick tube rising from the reservoir and projected into said portion, a perforated slide plate removably held in the guide-ways, a burner tube supported above said portion and a burner at the free end of the said tube.

4. In a hydrocarbon burner, the combination of a reservoir, a wick in communication therewith, a member supported above said reservoir having a raised portion provided with guide-ways, a wick tube mounted on said reservoir and adapted to be slid with

said reservoir into position in said raised portion, a perforated plate adapted to be slid into said guide-ways after said wick is lighted in position, a burner tube above said 5 perforated plate provided with a perforated plate at one end and air openings near the other end.

In testimony whereof, I have signed my name to this specification, in the presence of two subscribing witnesses.

ALFRED KAUFMAN.
